UNITED STATES PATENT OFFICE.

WILLIAM S. CALCOTE, OF WELLINGTON, TEXAS.

DOOR-OPERATING MECHANISM FOR MAIL-BOXES.

1,216,067.

Specification of Letters Patent. Patented Feb. 13, 1917.

Application filed June 13, 1916. Serial No. 103,492.

To all whom it may concern:

Be it known that I, WILLIAM S. CALCOTE, a citizen of the United States, residing at Wellington, in the county of Collingsworth and State of Texas, have invented certain new and useful Improvements in Door-Operating Mechanism for Mail-Boxes; and I do hereby declare the following to be a full, clear, and exact description of the invention, such as will enable others skilled in the art to which it appertains to make and use the same.

The primary object of this invention is the provision of a novel type of door operating mechanism for mail boxes and like receptacles, that will admit of the door being conveniently and expeditiously opened and closed.

Another object of the invention is the provision of mechanism, for carrying out the above object, that will be of simple and durable construction, cheap to manufacture and efficient in operation.

Other objects will appear and be better understood from that embodiment of my invention of which the following is a specification, reference being had to the accompanying drawing forming a part thereof, in which:

Figure 1 is a side view of a receptacle with the door closed and showing the door operating mechanism associated with the receptacle.

Fig. 2 is a detail side view of the forward end of the receptacle, with the door opened, and

Fig. 3 is a forward end elevation of the receptacle with the door closed with the lower end of the lever in section.

Referring to the drawing in detail, the numeral 1 designates a receptacle, which for conventional purposes is shown in the form of a mail box, and has one end thereof provided with a door 2, the said door having its lower edge connected to the lower edge of the adjacent end of the receptacle 1 by means of the hinges 3. A latch bar 4 is associated with the door 2, and has one end thereof pivoted to the door, as shown at 5, and its opposite end extended through a guide 6 carried by the door and terminally extended beyond the adjacent side wall of the receptacle, as shown more clearly in Fig. 3 of the drawing. A keeper 7 has one end secured to that side wall of the receptacle beyond which the free end of the bar

4 projects, and the said keeper has one end projecting beyond the adjacent end of the receptacle and provided with a harbor or locking notch 8. A plate 9 is disposed below the keeper 7 and has connection with the adjacent side wall of the receptacle 1 and pivotally associated with the plate 9 is an operating lever 10, which has one end pivoted to the plate by means of a pivot bolt 11, and the free end of the lever 10 is curved, as shown at 12, to provide a gripping portion for the accommodation of the hand of the operator.

The operating lever 10 is provided with an opening 13, which receives the free end of the latch bar 4, and the lower wall of the opening 13 is inclined in the direction of the receptacle 1, as shown at 14.

When the door 2 is in closing position, the free end of the latch bar 4 is received by the notch 8 in the keeper 7, and the terminal of the free end of the latch bar 4 rests at the point of juncture between the lowermost end of the wall 14 and the adjacent vertical wall of the opening 13.

As means for normally holding the lever 10 in position, whereby the terminal of the free end of the latch bar 4 will rest at the lower end of the wall 14 of the opening 13, when the bar 2 is closed, a spring 15 is provided. This spring 15 has one end connected to a plate 16 carried by the rear end of that side wall of the receptacle 1, upon which the operating mechanism is mounted, and the opposite end of the spring 15 is connected to the lever 10 by means of a pin 17.

When it is desired to open the door 2, the lever 10 is pulled outwardly, causing the free end of the latch bar 4 to ride upwardly on the inclined wall 14 of the opening 13, and liberate the free end of the latch bar 4 from the notch 8 in the keeper 7, the pull being continued on the lever 10 causing the latch bar 4 to contact with the inner side wall of the opening 13 so as to effect movement of the door to the open position on the continued movement of the lever 10, as shown in Fig. 2 of the drawing. During the movement of the lever 10 to the position shown in Fig. 2, the spring 15 will be expanded, so that when the lever 10 is released the spring will return the door 2 and lever 10 to normal position, as shown in Fig. 1, resulting in the free end of the bar 4 returning to the notch 8 in the keeper 7.

A stop 18 is carried by the keeper 7 and is adapted to engage the inner edge of the lever 10, when the lever is in the position shown in Fig. 1, so as to limit the movement 5 of the lever and prevent strain being exerted on the free end of the latch bar 4.

The plate 9 is provided with a lateral extension 19, and the lever 10 has a bearing seat 20 formed therein which receives a 10 spherical head 21 carried by the bolt 11 so as to admit of the lever having a lateral as well as a vertical movement. The forward end of the plate 9 is extended beyond the adjacent end of the receptacle 1 and is reduced in thickness, as shown at 22, and the outer side of the reduced end is beveled, as shown in Fig. 3. A hook 23 has its shank connected to the lever 10 and its bill projecting beyond the inner longitudinal side of 15 the lever. When the lever 10 is lowered the bill of the hook 23 comes in contact with the beveled side of the reduced end 22 of the plate 9 and causes lateral deflection of the lever until the bill of the hook passes below 20 the plate 9, after which the lever is moved toward the plate 9 and the bill of the hook engaged over the lower edge of the reduced end of the plate 9, so as to admit of the lever being locked in lowered position and hold 25 the door 2 open to admit of the convenient insertion of large packages into the receptacle or the removal of the same from the receptacle.

Having thus described my invention what 30 I claim as new, is:

1. The combination with a receptacle having a door, of a keeper carried by the receptacle, a latch bar pivoted to the door having one end adapted to be operatively engaged by the keeper for normally holding the door closed, the said end of the latch bar having its terminal projecting beyond the keeper, a lever pivoted to the receptacle and having an opening therein for receiving 40 the extended terminal of the mentioned end of the latch bar, and means for moving the mentioned end of the latch bar from engagement with the keeper when the lever is moved in one direction so as to permit opening of the door.

2. The combination with a receptacle having a door, of a keeper carried by the receptacle, a latch bar pivoted to the door and having one end thereof adapted to be operatively engaged by the keeper, the said end of the latch bar having its terminal projecting beyond the keeper, a lever pivoted to the receptacle and having an opening therein for receiving the extended terminal of the 45 latch bar, means for moving the mentioned terminal of the latch bar within the opening

in the lever when the lever is moved in one direction so as to disengage the latch bar from the keeper so as to permit opening of the door, and means for returning the door 65 and lever to normal position.

3. The combination with a receptacle having a door therein, of a keeper mounted on the receptacle, a latch bar pivoted to the door and adapted to have one end thereof 70 operatively engaged by the keeper, the terminal of the mentioned end of the latch bar being extended beyond the keeper, a lever pivoted to the receptacle and having an opening therein for the reception of the extended terminal of the mentioned end of the latch bar, the lower wall of the opening being inclined and providing a rest for the terminal of the mentioned end of the latch bar when the lever is in normal position, the 75 said inclined wall being adapted to move the mentioned end of the lever upwardly in the opening when the lever is moved in one direction so as to release the latch bar from the keeper to admit opening of the 80 door.

4. The combination with a receptacle having a door therein, of a keeper mounted on the receptacle, a latch bar pivoted to the door and having one end adapted to be operatively engaged by the keeper when the door is closed, a lever pivoted to the receptacle and operatively engaging the latch bar for moving the latch bar from engagement with the keeper when the lever is moved in 95 one direction, so as to admit of the door being opened, means for returning the lever and door to normal position when the lever is released, and means for limiting the movement of the lever upon return of the 100 same to normal position.

5. In a receptacle having a door and an operating lever for the door, a plate mounted on the receptacle and having one end extended beyond the receptacle and reduced, 105 the outer side of the extended end being beveled, means carried by the lever for engaging the beveled side of the reduced end of the plate during movement of the lever in door opening direction so as to effect lateral 110 movement of the lever and adapted to be engaged beneath the reduced end of the plate when the lever reaches the end of its movement in a door opening direction so as to hold the lever against movement when the 115 door is opened.

In testimony whereof I affix my signature in presence of two witnesses.

WILLIAM S. CALCOTE.
